CLAIM

The ornamental design for a baffled material for apparel, as shown and described.

DESCRIPTION

FIG. 1 is a front elevation view of a baffled material for apparel shown in an environment of use as part of a zipped jacket;

FIG. 2 is a front perspective view of the baffled material of FIG. 1 with the jacket unzipped; and,

FIG. 3 is an enlarged perspective view of area 3 circumscribed within FIG. 2.

The broken lines depict the environment of a jacket that forms no part of the claimed design. The circular broken line in FIGS. 2 and 3 denotes the boundary of the detail area and forms no part of the claimed design.
